UNITED STATES PATENT OFFICE.

JAMES H. WAGENHORST, OF JACKSON, MICHIGAN.

BATTERY JAR.

Original application filed October 31, 1921, Serial No. 511,859. Renewed May 27, 1926. Divided and this application filed June 8, 1926. Serial No. 114,522.

My invention relates to improvements in battery jars and the method of making the same and has to do, more particularly with the manufacture of rubber battery jars such as are customarily used in connection with storage batteries. My invention relates particularly to an improved construction by means of which handles are attached to such jars.

10 This application is a division of my application Serial No. 511,859, filed October 31, 1921, and renewed May 27, 1926.

The principal object of my invention is to provide an improved connection between a handle and the battery jar proper, which may be constructed very simply and cheaply and in which the handle is fastened securely to the wall of the battery jar without at all weakening such wall. A further object of my invention is to provide a construction in which a handle is fastened to the wall of a battery jar by vulcanizing the rubber of the jar in place around projecting portions of said handle whereby the handle is securely fastened 25 and reinforces the wall of the battery jar and the connection does not weaken the wall.

Further objects, and objects relating to details and economies of construction and operation will definitely appear from the detailed description to follow. In one instance, I accomplish the objects of my invention by the devices and means set forth in the following specification. My invention is clearly defined and pointed out in the appended 35 claims. A structure constituting a preferred embodiment of my invention is illustrated in the accompanying drawings, forming a part of this specification, in which:

Figure 1 is a perspective view of a battery jar embodying my invention, and

Fig. 2 is a detail, sectional view through one end wall of the jar and the handle showing the manner in which the handle is connected to the jar.

45 In the drawings, the same reference numerals refer to the same parts throughout the several views.

In general, I accomplish the objects of my invention by providing a handle having a se-

ries of holes therethrough and by pressing 50 this handle against the rubber forming the wall of the battery jar, while that rubber is soft and before it has been vulcanized. This causes the soft rubber to penetrate the holes in the handle and forms an interlock 55 between such rubber of the battery jar wall and the handle. The battery jar is then vulcanized which hardens this rubber and causes it to securely lock the handle in place. I propose to provide the holes in the plate forming 60 the handle with counter-sinks on the side facing away from the wall of the battery jar and the rubber which penetrates through the holes will flow over these counter-sinks and thus make a better interlock between the handle 65 and the battery jar.

In the drawings, I have illustrated one embodiment of my invention comprising a battery jar 10 formed of rubber molded about a mandrel and then vulcanized into the required form. The handles 11 are provided one on each end of the battery jar each handle comprising a plate portion having in its upper end a slit 12 forming a grip, by means of which a workman may grasp the handle and thus lift the battery jar. The plate portion of the handle 11 is provided with a series of holes 13 therethrough, each of which is provided with a counter-sunk portion 14 on the side facing away from the wall of the battery jar. After the battery jar has been formed, but before it has been vulcanized to harden the rubber, the plate 11 forming the handle is pressed against the wall of the battery jar and this causes the soft rubber to 85 penetrate the holes 13 and to flow into the counter-sinks 14, as illustrated at 15 in Fig. 2. The battery jar is then vulcanized, which causes the rubber to set or harden and forms a very secure and strong interlock between 90 the wall of the battery jar and the handle. In this way, the handles are securely fastened in place in a very simple and economical manner but without weakening at all the walls of the battery jar.

95 I am aware that my invention is susceptible of considerable variation without departing from the spirit thereof, and, therefore, I

claim my invention broadly as indicated by the appended claim.

What I claim is:

The combination of a jar of vulcanized rubber, a handle member therefor having a body portion applied to and lying against the side wall of such jar and provided with a plural-

ity of perforations having outwardly flaring walls, the outer face of said body portion being exposed, and a plurality of integral rivet-like extensions formed of the rubber of said jar and extruded through and filling said perforations to secure the handle to the jar. 10

JAMES H. WAGENHORST.
